UNITED STATES PATENT OFFICE.

CHARLES C. WIENTGE, OF PROVIDENCE, RHODE ISLAND, ASSIGNOR TO THE HOWARD STERLING COMPANY, OF SAME PLACE.

DESIGN FOR A CANDELABRUM-PEDESTAL.

SPECIFICATION forming part of Design No. 23,181, dated April 10, 1894.

Application filed March 8, 1894. Serial No. 502,909. Term of patent 7 years.

To all whom it may concern:

Be it known that I, CHARLES C. WIENTGE, of Providence, in the county of Providence and State of Rhode Island, have invented and produced a new and original Design for Candelabrum-Pedestals, of which the following is a complete specification, reference being had to the accompanying drawings, forming part thereof.

- 10 Figure 1 represents an elevation of a candle-stick illustrating my design. Fig. 2 represents a cross-sectional view of the same taken on a line *a—b*, Fig. 1, looking downward.
- 15 The leading features of my design consist in the shape and ornamentation of the pedestal, having a central, inverted, truncated, elongated, conical appearance, surmounted by a circular concave rim and supported on
- 20 the concave conical base having a hexagonal edge.

In the drawings 5 represents the conical base having an edge divided into vertical hexagonal planes 6—6 and a concave surface contracting in diameter toward the upper portion, supported on this base is the trun-

cated body 7 having the hexagonal panels 8—8 which extend downward in convex planes contracting in diameter until they reach the circular bead 9 which forms the 30 point of juncture between the base and the body, the general appearance of this portion of which is that of an inverted truncated cone somewhat elongated. Above the panels 8—8 the body assumes a circular concave 35 form 10 contracting in diameter toward the upper portion where it is ornamented by the circular convex beading 11 forming the base for the hexagonal convex panels 12—12 the width of which gradually increases toward 40 the top, above these panels is a concave circular portion which first contracts in diameter and then enlarges.

What I claim is—

The design for a candelabrum pedestal as 45 herein shown and described.

In witness whereof I have hereunto set my hand.

CHARLES C. WIENTGE.

Witnesses:

HENRY J. MILLER,
M. F. BLIGH.
